CLAIM

The ornamental design for a housing for a telephone handset, substantially as shown and described.

DESCRIPTION

FIG. 1 is a top and side perspective view from above of a housing for a telephone handset showing our new design;

FIG. 2 is a side elevational view thereof, it being understood that the view of the side opposite to that shown is substantially a mirror image; and

FIG. 3 is a bottom plan view thereof.

FIG. 1

FIG. 2

FIG. 3
